UNITED STATES PATENT OFFICE.

JAMES R. CARDWELL, OF CHICAGO, ILLINOIS.

WALLET.

1,035,945.

Specification of Letters Patent. Patented Aug. 20, 1912.

Application filed November 17, 1910. Serial No. 592,793.

To all whom it may concern:

Be it known that I, JAMES R. CARDWELL, citizen of the United States, residing at Chicago, in the county of Cook and State of Illinois, have invented a certain new and useful Improvement in Wallets, of which the following is a full, clear, concise, and exact description, reference being had to the accompanying drawings, forming a part of this specification.

My invention relates to wallets, and has for its object the production of a very simple form of wallet for holding folded bank notes.

My invention may generally be described as being a wallet comprising a substantially flat oblong sheet of suitable wallet material presenting a superficial area having dimensions substantially in proportion to the dimensions of the bank note that is folded on a longitudinal line to divide the bank note into two substantially equal divisions, said sheet of wallet material being foldable upon itself along a transverse line, and a bank note holding wing joined with a longitudinal side portion of the sheet and located substantially upon one side of the transverse line of fold for the sheet.

In the preferred embodiment of my invention I employ two wings that are joined with the main wallet sheet, one being located on each side of the transverse line along which said sheet is foldable, these wings desirably being joined with the opposite longitudinal edges of the wallet sheet so as to project in opposite directions and thereby operating to prevent the interfolded bank notes from becoming dislodged by their movement transversely of the wallet sheet.

I will explain my invention more fully by reference to the accompanying drawing showing the preferred embodiment thereof and in which—

Figure 1 is a view of the preferred form of wallet with the wallet sheet laid flat, a bank note folded lengthwise to occupy substantially half its full area being shown by a dot and dash line where exposed to view and by a dotted line where concealed by one wing; Fig. 2 is a side elevation with the wallet sheet partially folded, the bank note being omitted for clearness; Fig. 3 is a view looking in the direction of arrow 3 Fig. 2, bank notes being shown in full lines; and Fig. 4 is a transverse sectional view taken

through the wings of the wallet when folded, the bank note being shown in full lines.

Like parts are indicated by similar characters of reference throughout the views. 60

As the preferred embodiment of my invention is shown I employ a substantially flat oblong sheet of suitable wallet material 5 which presents a superficial area having dimensions substantially in proportion to the dimensions of a bank note 6 or a thin pile of superposed bank notes when such bank note or pile of bank notes is folded on a longitudinal line to divide the bank note or notes into two substantially equal divisions. 65 The sheet of wallet material is foldable into two substantially equal divisions along a transverse line as indicated at 7, the bank note holding wings 8 being preferably entirely located on opposite sides 70 of the line 7 to permit the ready folding of the wallet sheet, and projecting from opposite longitudinal sides of the wallet sheet in such opposite directions as to overlie the folded money and prevent dislodgment 75 thereof by sidewise movement, one wing projecting between the fold layers of the bank note or notes and serving to separate them so that the place where the notes are to be unfolded and laid flat may readily be determined, while all of the bank note layers are interposed between the other wing and the wallet sheet. The wings are preferably 80 separately formed and thereafter attached to the main wallet sheet, but I do not wish 90 to be limited to wings separately made and thereafter joined as the wings may be joined with the wallet sheet by being made therewith out of an integral sheet of wallet material. 95

Having thus described my invention I claim as new and desire to secure by Letters Patent the following:

1. A wallet comprising a rectangular sheet of suitable wallet material having a longitudinal dimension slightly longer than a bank-note, and a transverse dimension slightly greater than one-half the width of a bank-note and adapted to receive upon its upper face a plurality of bank-notes folded longitudinally, said rectangular sheet being provided with a transverse folding line at its middle, and having means located at one side thereof between the folding line and one end of the said sheet to retain the folded bank notes in position upon the sheet when the wallet is open.

2. A wallet comprising a rectangular sheet of suitable material having a longitudinal dimension slightly longer than a bank-note and a transverse dimension slightly greater than one-half the width of a bank-note, and adapted to receive upon its upper face a plurality of bank-notes folded longitudinally, said rectangular sheet being provided with a transverse folding line at its middle, and having means disposed on the opposite sides of the sheet and on opposite sides of said folding line to embrace and retain in position bank-notes disposed on the sheet when the wallet is open.
3. A wallet comprising a rectangular sheet of suitable material having a longitudinal dimension slightly longer than a bank-note and a transverse dimension slightly greater

than one-half the width of a bank-note, and adapted to receive upon its upper face a plurality of bank-notes folded longitudinally, said rectangular sheet being provided with a transverse folding line at its middle, and having a wing on each side of the said sheet and on opposite sides of said folding line extending inwardly over the sheet and adapted to embrace and retain in position bank-notes disposed on the sheet when the wallet is open.

In witness whereof, I hereunto subscribe my name this 14th day of November A. D., 1910.

JAMES R. CARDWELL.
